AMPLIFIER TUBE AND CIRCUIT

William Joseph O'Brien, Chicago, Ill., assignor to
 Radio Corporation of America, a corporation
 of Delaware

Application December 27, 1934, Serial No. 759,327

2 Claims. (Cl. 179—171)

An object of this invention is to provide an amplifier tube and circuit which is adapted to amplify currents which have a wide range of frequency, which currents may be of either audio or radio frequency, the amplifier being arranged to amplify currents of the different applied frequencies substantially equally.

A further object of the invention is to provide an electronic discharge device which has a plurality of grids one of which serves as a screen grid and is so arranged that its voltage varies in phase with that of the signal control grid.

A still further object of the invention is to provide a vacuum tube having a plurality of grids including a signal control grid and a fourth grid located between the cathode and the signal control grid, this grid being connected and arranged to keep the current flowing to the screen grid from increasing excessively when the screen voltage is made positive by a substantial amount.

Other objects of the invention will become apparent to those skilled in the art as the description thereof proceeds. For a better understanding of the invention, however, reference is made to the following specification taken in connection with the attached drawing which shows one embodiment of the invention.

In the drawing.

Figure 1 is a schematic circuit diagram of an amplifier arrangement constructed according to the invention and,

Figure 2 is a schematic diagram showing the arrangement of several electrodes within the tube.

Referring first to Figure 2, the vacuum tube 20 comprises a cathode C which is heated to electron emitting temperature by a heater or filament 21 and a first grid 1 which, as shown, is connected to the cathode within the tube but this connection may be by a lead 17 outside the tube, as shown in Figure 1. The second grid 2 is shown connected to the fourth grid 4 within the tube and between these grids is located the signal control grid 3. The tube also has the usual output electrode or plate 6, and, as shown, has an auxiliary grid 5 located between the plate and grid 4. Suitable lead wires are connected within the tube to the several elements thereof and pass through the tube envelope to the exterior thereof.

As shown in Figure 1, two tubes of the type described, are connected together to form an aperiodic amplifier, an input circuit comprising resistor 8 and grid bias battery 13 being connected between grid 3 and the cathode C of the first stage. Any suitable source of voltage of

variable frequency may be connected to the terminals of resistor 8. As shown in the drawing such source is a photoelectric cell 9 whose terminals are connected to the terminals of resistor 8. The currents generated by the cell 9 may be of audio or radio frequency type, depending on the use to which the amplifier is to be put, and while I have shown a photo-cell as a source of variable frequency currents it will be understood that any other signal voltage source of either audio or radio frequency type may be used instead. As shown, the positive terminal of the plate battery 15 is connected to the plate through a high resistance 10 and grids 2 and 4 connected to an intermediate point of the battery through a resistor 12. Also the grid 5 is shown connected to another intermediate point of the battery of higher potential but it will be understood that this connection may be omitted and the grid 5 directly connected to the cathode so that this grid operates as a suppressor grid. As shown, the battery connections to the several elements of the second tube are the same as those of the first and therefore need not be further described. Also as shown, the plate of the first stage is coupled to the control grid 3 of the second stage through a condenser 7 and the amplified voltage is obtained across the output terminals 18 at the ends of resistor 10 of the second stage. These output terminals, it will be understood, may be connected to any desired utilization device in any known manner. The capacity between the input terminals of the first stage is designated by the condenser 14 which is dotted as this is inherent capacity and not a physical condenser.

It is known that an amplifier which must give fairly uniform amplification for signals covering a wide range of frequencies beginning at the lower end of the audio range and extending into the radio frequency range has a limitation in the upper range due to the capacity of the input and output circuits of the several stages. In the usual amplifier tube when a signal voltage is applied to the grid, the grid and plate voltages are of opposite phase and therefore the voltage between these elements is equal to the gain plus one times that which exists between grid and ground or cathode. The signal current from grid to plate through the capacity between these elements will be increased by an amount equal to the voltage increase. This is in fact an increase of input capacity by an amount equal to the gain times the grid to plate capacity. This effect has been substantially eliminated by the use of screen grid type tubes and these tubes perform

much better than triodes for amplifying a wide range of frequencies.

I have found that a screen or auxiliary grid which is actuated by a potential which is in phase with that of the control grid will effectively decrease to a considerable extent the capacity of the input circuit for the same reason that the 180° difference in potential between control grid and plate effects an increase. This result may be accomplished as shown in Fig. 1 by providing at least one grid such as the grid 2 adjacent the grid 3 so that it has a negative trans-conductance with respect to the latter. In my device, grid 1 substantially limits the total current emitted from the cathode and prevents the voltage variation of grid 2 from substantially changing this current value. As grid 1 limits the total emission current from the cathode, the current to plate 6 plus the current to grid 2 must equal a constant value, as they make up the total cathode current. Therefore any increase in current to plate 6 from whatever cause which does not affect the total cathode current must be accompanied by a corresponding decrease in the current to grid 2. Due to the relative position of the grids and plate in the tube a more positive potential applied to grid 3 produces an increase in the velocity of the electrons toward plate 6 in the region of grid 3 thereby allowing more of them to pass beyond this region and travel to the plate. These electrons otherwise would have passed to grid 2, and therefore the number passing to this grid has been decreased. When control grid 3 is made more positive by the applied signal voltage the current through resistor 10 increases and the voltage of plate 6 decreases; but at the same time, due to the relative positions of the grids, the current flowing to grid 2 decreases so that the voltage of point 11 and grid 2 likewise increase or, in other words, the trans-conductance of grid 2 with respect to grid 3 is negative so that the voltage variations of grids 2 and 3 occur in phase whereas those of grid 3 and plate 6 are out of phase. Grid 5 acts as a shield grid between grid 4 and plate 6 and prevents an effective increase of capacity between them due to the voltage variation of the plate occasioned by the signal voltage. Grid 5 may be operated either as a suppressor or a screen grid, its use depending on the negative trans-conductance of grids 2 and 4 with reference to grid 3.

In the circuit shown in Figure 1, the resistors 12 control the gain between grid 3 and grid 2. When this gain is made unity by choice of a proper value of resistor 12, grid 3 and grids 2 and 4 will upon application of a signal voltage, fluctuate in potential equally and in phase with each other so that they will remain at the same radio frequency potential and will, therefore, give the result of an infinite input impedance. If resistor 12 is so proportioned as to make the gain greater than this amount the result will be that the input will be equivalent to a negative capacity in series with a negative resistance.

This negative capacity transferred to the input circuit will balance out the positive capacity 14 transferred thereto by the inherent capacity between the circuit of plate 6 and that of grid 3 including the capacity between these elements 5 within the tube. It will be understood that any undesired capacity 14 in the input circuit causes the amplification to fall off fairly rapidly as the applied frequency is increased but by means of this invention this capacity may be neutralized 10 or compensated for by the negative capacity provided by grid 3 in connection with grids 2 and 4. By making the gain of that portion of the tube including grids 3 and 2 greater than unity as by a proper choice of the value of resistor 12, the inherent capacity 14 may be completely compensated for and with the result that all the frequencies within the range to be amplified are amplified substantially equally. The increased amplification of the high frequencies over the 20 usual triode amplifier as provided by the first stage is effected in substantially the same manner in the second stage so that the effect of the two stages is cumulative and it will be understood that further similar amplification stages may be 25 added if desired. I have found the following values to give satisfactory results in the arrangement described; resistor 10 may have a value substantially equal to the plate resistance of the tube, resistor 12 has a value of 4,000 ohms when the 30 negative transconductance of grid 2 has a value of 300 micromhos, resistor 8=500 megohms.

While I have shown my invention in a single embodiment thereof it is to be understood that it is not restricted to the specific embodiment shown 35 and is limited only by the scope of the following claims and the prior art.

Having described my invention what I claim as novel and desire to secure by Letters Patent is:

1. An aperiodic amplifier for amplifying currents covering a wide band of frequencies, comprising the combination of an electronic tube having a cathode, a signal control grid, a plate, a screen grid located between said cathode and control grid, third and fourth grids located between 45 said signal control grid and plate, an input circuit connecting said signal control grid and cathode including means for providing a negative bias potential to said control grid, a source of steady potential having its negative terminal connected to said cathode, a circuit including an impedance connecting the positive terminal of said potential source and said plate, means for maintaining said fourth grid at a steady positive potential which is less than that of said potential source, and a resistor having one end connected to an intermediate point of said potential source and its opposite end to said screen grid and also to said third grid. 55

2. An aperiodic amplifier according to claim 1, 60 wherein the electronic tube is provided with an auxiliary grid positioned between the screen grid and the cathode, said auxiliary grid being at cathode potential.

WILLIAM JOSEPH O'BRIEN.
